ERNEST DAVIS, OF SYRACUSE, NEW YORK, ASSIGNOR TO THE PROSPERITY COMPANY INC., OF SYRACUSE, NEW YORK, A CORPORATION OF NEW YORK

ELECTRIC MOTION TRANSMITTING MECHANISM AND CONTROLS FOR PRESSING MACHINES

Application filed October 11, 1929. Serial No. 398,965.

This invention relates to machines having an opening and closing movement, as garment and laundry pressing machines, and has for its object, a particularly simple, efficient and compact electric motor actuating mechanism for closing the press, and controls for said actuating mechanism.

The invention consists in the novel features and in the combinations and constructions hereinafter set forth and claimed.

In describing this invention, reference is had to the accompanying drawings, in which like characters designate corresponding parts in all the views.

Figure 1 is a side elevation, partly broken away, of a conventional garment or laundry press embodying my invention.

Figure 2 is a diagrammatic view of the actuating mechanism and the controls therefor.

I have here illustrated my invention as embodied in a conventional type of garment or laundry press in which the cooperating pressing elements are respectively, a buck 1 and a head 2 movable toward and from the buck, the buck being mounted on a suitable bracket or bolster 3 which in turn is mounted upon a suitable frame 4; and the head being carried by a lever 5 pivoted between its ends at 6 to an upright 7 rising from the frame 4.

The actuating mechanism comprises an electric motor and electrically operated motion transmitting means between the motor and the press head 2.

8 designates the electric motor.

9 designates the electric motion transmitting mechanism, which we shall call for convenience, a second motor. The second motor includes a rotating armature 10, the shaft 11 of which is connected to an armature shaft 12 of the motor 8 in any suitable manner, as by a coupling 13.

14 is a casing which carries rotatable field coils 15 of the second motor 9, the casing 14 being connected to the head 2 by suitable motion transmitting means.

The motion transmitting means here illustrated, in addition to the lever 5, comprises a link 16 pivoted at one end at 17 to a radial arm 18 on the casing 14, and at its other end at 19 to the rear arm of the lever 5. The press

is opened when the second motor 9 is deenergized by a counterspring 20.

In the normal operation of the machine, when the press is open the motor 8 is preferably constantly running and is connected in the feed circuit 21 and 22 by a circuit including a wire 23, blade 24 of a double pole switch, conductor 25, wire 26 which is connected to one of the terminals of the motor 8, the motor 8, wire 27 connected to the other terminal, the other blade 28 of the double pole switch, and wire 29. The double pole switch and also a cut-out snap switch 30 in the conductor 26 are closed in the normal operation of the machine, so that power is constantly supplied to the motor 8.

The second motor 9 is connected to the feed wires 21 and 22 through a branch circuit consisting of wire 23, blade 24 of the double pole switch, wire 25, wire 31, switch 32, switch contact 33, wire 34, switch 35, switch contact 36, wire 37, brush 38, the armature and field coils of the motor 9, brush 39, wire 40, wire 27, switch blade 28 of the double pole switch, and wire 29. The switches 32 and 35 are normally open and are manually operable as by push buttons 41 and 42 connected to the switches by links 43 and 44 respectively, these push buttons being acted upon by springs 45 and 46 which tend to open the switches 32 and 35 when the push buttons are released. Although two push buttons are shown, obviously, one push button or one switch may be employed. Two switches are used connected in series in order that both hands of the operator may be employed while the press is closing. The motor 9 is similar to a torque motor and may be shunt, series or compound wound.

Means is provided for holding the press closed when the push buttons 41 and 42 are released, this means being controlled by the closing of the press. This means as here shown comprises, a normally open tumbler switch 47 in a shunt circuit around the switches 32, 35, this switch being operable by the motion transmitting means between the motor 9 and the press head and so arranged as to be operated or closed when the press reaches nearly closed position.

The switch 47 is here shown as mounted on the back leg of the frame and as having a movable member 49 acted on by a lever 49^a connected to a push link 49^b arranged in the path of the link 16 to be engaged and operated by the link when the link approaches its position assumed when the press is closed, the link 16 also holding the switch member 49 in its closed position. The switch is provided with means, as a spring 50, for opening it when released.

In order to open the press, a normally closed release switch 51 is provided, in the shunt circuit, having means as a spring 52 tending to close it and being operable into open position by a trip lever 53. The switch 51 is connected to a wire 54 which is connected to the wire 37 and coacts with a contact 55 which is connected by a wire 56 to the terminal 57 with which the switch 47 coacts. The other terminal 58 of the switch 47 is connected by a wire 60 to the wire 25. The switch 47 may be of any suitable form, size and construction.

In operation, upon depression of the push buttons 41 and 42, the switches 32 and 35 are closed against the action of their returning springs 45 and 46 so that the second motor 9 is energized and the rotation of the armature shaft 12 of the motor 8 transmitted through the armature and field of the motor 9 and link 16 to the press head carrying lever 5 to close the press. When the press approaches closed position, the motion transmitting link 16 throws the switch 47 to close the shunt circuit around the switches 32 and 35 so that the circuit through the second motor 9 remains closed after the operator releases the push buttons 41 and 42 and the press remains closed as long as desired under influence of the torque developed by the motor 8. To open the press, the trip lever 53 is actuated to open the switch 35 and thus deenergize the second motor 9, whereupon the press opens under the influence of the countersprings 20. The motor 9 acts as a magnetic clutch between the motor 8 and the motion transmitting means which connect with the movable pressing element. When the armature and field coils of the motor 9 are deenergized the clutch is in effect released and the motor 8, which is constantly supplied with energy will again rotate. The motor 8 is thus continuously rotating at all times except when the press is closed under pressure and this continuous operation provides the advantage that the motor possesses momentum which renders the operation of the press faster when the armature and field coils of the second motor 9 are energized to clutch the motor 8 to the motion transmitting means.

What I claim is:

1. A pressing machine comprising cooperating pressing elements, one of which is mov-

able toward and from the other, actuating mechanism comprising an electric motor and motion transmitting means between the electric motor and the movable element including a second electric motor having a rotating armature and a rotatable field, the armature being connected to the rotor of the first motor to be actuated thereby, and motion transmitting connections between the rotatable field and the movable element, an electric circuit having branches connected to the motors to energize the same, and a manually operable switch in the branch connected to the second motor.

2. A pressing machine comprising cooperating pressing elements, one of which is movable toward and from the other, actuating mechanism comprising an electric motor and motion transmitting means between the electric motor and the movable element including a second electric motor having a rotating armature and a rotatable field, the armature being connected to the rotor of the first motor to be actuated thereby, and motion transmitting connections between the rotating field and the movable element, an electric circuit having branches connected to the motors to energize the same, a normally open, manually operable switch in the branch connected to the second motor, said switch having means tending to open it when released, a normally open switch connected in shunt with the former switch in the branch connected to the second motor and having means tending to open it, means controlled by the closing of the press to close the switch in the shunt circuit, and a normally closed, manually operable switch in said shunt circuit.

3. A pressing machine comprising cooperating pressing elements, one of which is movable toward and from the other, actuating mechanism for closing the press, said actuating mechanism comprising an electric motor and motion transmitting means between the electric motor and the movable element including a second electric motor having a rotating armature and a rotatable field, the armature being connected to the rotor of the first motor to be actuated thereby, and motion transmitting means between the field and the movable press element, an electric circuit having branches connected to the motors to actuate the same, and a normally open, manually operable switch in the branch connected to the second motor.

4. A pressing machine comprising cooperating pressing elements, one of which is movable toward and from the other, actuating mechanism for closing the press, said actuating mechanism comprising an electric motor, and motion transmitting means between the electric motor and the movable element including a second electric motor having a rotating armature and a rotatable field, the

- armature being connected to the rotor of the first motor to be actuated thereby, and motion transmitting means between the field and the movable press element, an electric circuit having branches connected to the motors to actuate the same, and a normally open, manually operable switch in the branch connected to the second motor, a normally open switch connected in shunt with the former switch and having means tending to open it, and means operated by the press during the closing thereof for closing and holding closed the switch in the shunt circuit. 5. A pressing machine comprising cooperating pressing elements, one of which is movable toward and from the other, actuating mechanism for closing the press, said actuating mechanism comprising an electric motor, and motion transmitting means between the electric motor and the movable element including a second electric motor having a rotating armature and a rotatable field, the armature being connected to the rotor of the first motor to be actuated thereby, 10 and motion transmitting means between the field and the movable press element, an electric circuit having branches connected to the motors to actuate the same, and a normally open, manually operable switch in the branch connected to the second motor, a normally open switch in shunt with the former switch and having means tending to open it, and means operated by the press during the closing thereof for closing and holding closed 15 the switch in the shunt circuit, and a normally closed, manually operable release switch in the shunt circuit. 6. A pressing machine comprising cooperating pressing elements, one of which is movable toward and from the other, actuating mechanism for closing the press, said actuating mechanism comprising an electric motor and motion transmitting means between the electric motor and the movable element including a second electric motor having a rotating armature and a rotatable field, the armature being connected to the rotor of the first motor to be actuated thereby, motion transmitting means between the rotatable field and the movable pressing element, an electric circuit having branches connected respectively to the motors, a manually operable, normally open switch in the branch connected to the second motor having means 20 tending to open it when released, and means controlled by the closing of the press for closing the circuit independently of said switch when the movable element approaches closed position. 7. A pressing machine comprising cooperating pressing elements, one of which is movable toward and from the other, actuating mechanism for closing the press, and means to open the press, the actuating mechanism comprising an electric motor and motion transmitting means between the electric motor and the movable element including a sec- 25
- tion transmitting means between the electric motor and the movable element including a second electric motor having a rotating armature and a rotatable field, the armature being connected to the rotor of the first motor to be actuated thereby, motion transmitting means between the rotatable field and the movable pressing element, an electric circuit having branches connected respectively to the motors, a manually operable, normally open switch in the branch connected to the second motor having means tending to open it when released, and means controlled by the closing of the press for closing the circuit independently of said switch when the movable element approaches closed position. 8. A pressing machine comprising cooperating pressing elements, one of which is movable toward and from the other, actuating mechanism for closing the press, said actuating mechanism comprising an electric motor and motion transmitting means between the electric motor and the movable element including a second electric motor having a rotating armature and a rotatable field, the armature being connected to the rotor of the first motor to be actuated thereby, connections between the rotatable field and the movable element, an electric circuit having branches connected to the motors to actuate the same, and a pair of manually operable control switches in the circuit in the branch connected to the second motor. 9. A pressing machine comprising cooperating pressing elements, one of which is movable toward and from the other, actuating mechanism for closing the press, means to open the press, the actuating mechanism comprising an electric motor and motion transmitting means between the electric motor and the movable element including a second electric motor having a rotating armature and a rotatable field, the armature being connected to the rotor of the first motor to be actuated thereby, connections between the rotatable field and the movable element, an electric circuit having branches connected to the motors to actuate the same, and a pair of manually operable control switches in the circuit in the branch connected to the second motor, and means connected in the branch connected to the second motor for holding the circuit closed to the second motor when said switches are opened, said means being controlled by the closing of the press. 10. A pressing machine comprising cooperating pressing elements, one of which is movable toward and from the other, actuating mechanism for closing the press, means to open the press, the actuating mechanism comprising an electric motor and motion transmitting means between the electric motor and the movable element including a sec-

ond electric motor having a rotating armature and a rotatable field, the armature being connected to the rotor of the first motor to be actuated thereby, connections between the rotatable field and the movable element, an electric circuit having branches connected to the motors to actuate the same, and a pair of manually operable control switches in the circuit in the branch connected to the second motor, and means connected in the branch connected to the second motor for holding the circuit closed to the second motor when said switches are opened, said means being controlled by the closing of the press, and a normally closed release switch having means tending to close it connected in the branch to the second motor.

11. In a garment or laundry pressing machine cooperative pressing elements, one of which is movable toward and from the other; actuating mechanism comprising an electric motor and motion transmitting means between the electric motor and the movable element including a second electric motor having a rotatable armature and a rotatable field, one of which is connected to the rotor of the first motor to be actuated thereby, and the other of which is connected by motion transmitting means to the movable element; an electric circuit having branches connected to the motors to energize the same; and a manually operable switch in the branch connected to the second motor.

12. In a garment or laundry pressing machine cooperative pressing elements, one of which is movable toward and from the other; actuating mechanism for closing the press, said actuating mechanism comprising an electric motor and motion transmitting means between the electric motor and the movable element including a second electric motor having a rotatable armature and a rotatable field, one of which is connected to the rotor of the first motor to be actuated thereby, and the other of which is connected by motion transmitting means to the movable pressing element; an electric circuit having branches connected to the motors to supply energy thereto; and a normally open, manually operable, switch in the branch connected to the second motor.

13. In a garment or laundry pressing machine cooperative pressing elements, one of which is movable toward and from the other; actuating mechanism for closing the press, said actuating mechanism comprising an electric motor and motion transmitting means between the electric motor and the movable element including a second electric motor having a rotatable armature and a rotatable field, one of which is connected to the rotor of the first motor to be actuated thereby, and the other of which is connected by motion transmitting means to the movable pressing element; an electric circuit having branches

connected respectively to the motors; a manually operable, normally open, switch in the branch connected to the second motor, and means tending to open said switch when released; and means controlled by the closing of the press for closing a circuit independently of said switch when the movable element approaches closed position.

14. In a garment or laundry pressing machine cooperative pressing elements, one of which is movable toward and from the other; actuating mechanism for closing the press, said actuating mechanism comprising an electric motor and motion transmitting means between the electric motor and the movable element including a second electric motor having a rotatable armature and a rotatable field, one of which is connected to the rotor of the first motor to be actuated thereby, and the other of which is connected by motion transmitting means to the movable pressing element; an electric circuit having branches connected to the motors to supply energy thereto; and a pair of manually operable control switches in the branch circuit connected to the second motor.

In testimony whereof, I have hereunto signed my name, at Syracuse, in the county of Onondaga, and State of New York, this 4th day of October, 1929.

ERNEST DAVIS.
